TENNIS PRACTICE MACHINE

Edmundo H. Serrano, St. Louis, Mo., assignor to
Luella J. Serrano, St. Louis, Mo.

Application October 26, 1934, Serial No. 750,219

5 Claims. (Cl. 273—29)

This invention relates to tennis practice machines adapted to project a series of tennis balls at a player in varied trajectories and angles.

The primary object of this invention is to provide a device of the above mentioned character which is entirely automatic and which requires no attention whatsoever once the machine has been placed in operation.

A further object of this invention is to provide a machine of the above mentioned character having a wheeled frame to which is pivotally secured a ball carrying frame having a striker adapted to project balls in different heights.

15 A still further object of this invention is to provide a device of the above mentioned character having a ball striking member provided with two or more striking faces which will project a tennis ball in different horizontal angles.

20 A still further object of this invention is to provide means for feeding tennis balls at spaced intervals to a support directly in the path of the striking device and said means includes a novel arrangement comprising a receptacle having a series of chutes for receiving balls and novel means for allowing the dispensing of one ball 25 at a time from said chutes.

A further object of this invention is to provide a support upon which the tennis balls are fed so as to be positioned in the path of the striking device and said support is provided with a plurality of surfaces adapted to cause irregularities in the travel of the ball after being struck by the striking member.

30 35 A further object of this invention is to provide a striking member for a machine of the above mentioned character, the movements of which will simulate the action of a human player.

40 45 A still further object of this invention is to provide a device of the above mentioned character controlled by an automatic switch whereby a predetermined number of balls may be projected after which the machine will be completely turned off and will become inoperative.

A still further object of this invention is to provide a rotary brush in a tennis ball receptacle adapted to re-knap and clean the balls prior to their release upon the ball support in the 50 path of the striking member.

A still further object of this invention is to provide means for regulating the force of the blow struck by the striking element whereby tennis balls may be projected varied distances.

55 Other objects and advantages of the invention

will become apparent during the coarse of the following description forming a part of the specification and in which,

Figure 1 is a top plan view of the device embodying this invention illustrating the tennis ball receptacle and its circularly arranged chutes with respect to the striking element; 5

Figure 2 is a vertical front plan view partly in section illustrating the tennis ball receptacle in detail and further showing its relation with respect to the striking element and the other cooperative parts; 10

Figure 3 is a side plan view of the device embodying this invention illustrating the striker arm and the details of the operating construction along with other associated elements; 15

Figure 4 is a transverse cross sectional view illustrating the drive arrangement and gearing for operating the several parts of the machine; 20

Figure 5 is a top plan view of the striking device showing the same greatly enlarged for the purpose of illustrating the details of construction; 25

Figure 6 is a side plan view of the striking member further illustrating the gut strings with respect to the playing surface; 30

Figure 7 is an end plan view showing the manner in which the gut strings are spaced and held in position;

Figure 8 is a fragmentary side view of a portion of the supporting frame and the adjustable connection between the tilting mechanism and the same carried by the frame plates. 35

In the drawings, wherein for the purpose of illustrating the invention and wherein like reference characters will be employed to designate like parts throughout the same, the reference character 10 will generally be employed to designate a wheeled frame formed of angle bars spaced and braced by cross bars 11. Through 40 the wheeled frame 10 extends an axle 12 on the ends of which are casters or rollers 13. The opposite end of the wheeled frame 10 is provided with a foot 14 whereby said frame may be levelled with respect to the ground. 45

A pair of handle bars 15 is pivoted to the wheeled frame as at 16 and the upper ends of the handle bars 15 are connected by a horizontal bar 17 so that the handle bars 15 may be moved outwardly so that the stops 18 will engage the wheel frame 10 and form a means of moving the machine from different positions to desired locations. 50

Extending upwardly from the wheeled frame 10 are opposite supports 19 riveted to the 55

wheeled frame as at 20 and having the upper ends thereof converging inwardly and connected as at 21. Pivotally mounted between the vertical frame members 19 as at 22 is a frame structure comprising angle bars 23 joined at their intermediate portions by plates 24 and the lower end of the frame is provided with a floor 25 to which is bolted an electric motor 26 having an armature shaft 27 upon which are 10 mounted pulleys 28 and 29.

Journalled in bearings 30 carried by a pair of opposite frame plates 24 as shown in Figure 4 is a shaft 31 on one end of which is fixed a collar 32 having a grooved pulley 33 so that a belt 34 15 may be trained thereover and around one of the armature shaft pulleys 28. The intermediate portion of the shaft 31 is provided with a worm 35 adapted to drive a shaft 36 at right angles to the shaft 31. One end of the shaft 36 is 20 journalled in an anti-friction bearing 37 secured in one of the frame plates 24 while the opposite end as at 38 is received in a bore 39 formed in a stub shaft 40 which is rotatably mounted in anti-friction bearings 41 mounted 25 in the opposite frame plate 24. Rigidly secured to one end of the stub shaft 40 is a striker arm 42 having a striking member on the outer end which will be hereinafter more fully described.

Power is imparted to the rotary shaft 36 by 30 means of a worm wheel 43 rigidly secured thereon and meshing with the worm 35 on the shaft 31. Carried by the worm wheel 43 is a collar 44 having a set screw 45 for rigidly securing the worm wheel 43 and collar 44 to the shaft 36 and secured to the collar 44 as at 46 is a disk 47 to which is pivotally secured a dog 48 held in place by a threaded stub shaft 49 locked by a nut 50.

Rigidly secured to the stub shaft 40 is a drum 51 to which is attached a notched wheel 52 adapted to be engaged by the pawl 48 thereby establishing a rigid connection between the shaft 36 with the stub shaft 40 at intervals. Anti-friction bearings 53 may be mounted 45 between the drum 51 and the pawl carrying disk 47 and said anti-friction bearings are similar to the anti-friction bearings 41 whereby free and easy rotation may be provided.

The construction above described will effect 50 the drive of the shaft 36 through the medium of the worm 35 and worm wheel 43 to cause the rotation of the pawl carrying disk 47 which pawl 48 will normally be urged toward the notched wheel 52 by means of a retention device 54 which will cause the clutching of the disk 47 with the toothed wheel 52 and will result in the drive of the stub shaft 40 through the drum 51. Attached to the drum 51 are straps 55 and 56 and interposed in the straps 60 55 and 56 are rubber straps 57 and 58. The rubber strap 58 has connected thereto a strap 59 which passes over a pulley 60 secured in a sheave 61 passing through the floor 25 of the frame and the opposite end of the strap 59 65 extends through an opening 62 in a pivoted lever 63 having one of its ends connected as at 64 to one of the frame members 23 while the opposite end is provided with a detent 65 adapted to engage a notched segment piece 66 secured also to one of the vertical frame pieces 23. By connecting the opposite end of the rubber strap 57 with the strap 59 it will be obvious that the tension of both straps 57 and 58 may be regulated to place the drum 51 under different degrees of tension.

When the pawl 48 is received within the notch in the notched wheel 52, the drum 51 will be rotated against the tension of the rubber straps 57 and 58 as the straps 55 and 56 will wind upon the drum 51 and elongate the 5 rubber straps 57 and 58. After the drum 51 has been rotated a predetermined portion of a revolution, the pawl 48 may be released from the notched wheel 52 by engaging a roller 67 rotatably mounted between the arms 68, which 10 arms are secured to one of the frame plates 24. The striking arm 42 is operated upon reverse rotation of the drum 51 after said drum has been rotated against the tension of the straps 55 and 56 and elastic elements 57 and 15 58 and after the pawl 48 has been released by the trip member secured to the frame in the path of the pawl 48.

Secured to the stub shaft 40 is a pulley 69 having a V-shaped groove 70 in which is positioned a friction member 71 having one of its ends as at 72 anchored to a bracket 73, suitably fastened to one of the side frame plate members 24 by means of a nut and bolt 75. The bracket 73 may be spaced from the frame plates 24 by 25 means of a washer 76 and the opposite end of the friction clamp 71 may be secured to a similar bracket 77 also secured to the frame member 24 by means of a nut and bolt 78 and as shown in Figure 3, a coil spring 79 is adapted to surround 30 a bolt 80 to which the opposite end of the friction element 71 is connected so that one end of the coil springs will engage the bracket 77 and the opposite end will engage a disk 81 on said bolt 80 whereby the friction band 71 may be 35 placed under tension in order to brake the rotation of the stub shaft 40 without shock and place the same under friction.

Carried by the upper end of the vertical frame member 23 is a receptacle 83 having a sloping bottom 84 around which is positioned a shell 85 for the purpose of strengthening the construction. Arranged around the inner circumference of the receptacle 83 are chutes or guides 86 adapted to contain tennis balls in stacked 45 relation and said balls are adapted to rest upon an annular shelf 87 to limit the downward travel 50 of the tennis balls within the chutes 86. The chutes 86 are carried by a disk 88 secured to the upper end of a hollow shaft 89, the lower 55 end of which is journalled in a frame piece 90 and is provided with a worm wheel 91 adapted to mesh with a worm 92 rigidly secured to the drive shaft 36. The annular shelf 87 is provided with openings of sufficient diameter as at 94 60 and 94a for the passage of tennis balls whereby one ball at a time may be passed beneath the annular shelf 87 and into a chamber 95 as shown by dotted lines in Figure 2, where they are dispensed through an opening 96a onto the support 97. Slidably secured to the shelf 87 is an adjustable plate 94b adapted to alternately 65 cover the openings 94 and 94a and said plate may be adjusted by means of a thumb screw 94c. If the plate 94b is positioned over the opening 94, 70 the tennis balls will travel a complete revolution in the chamber 95 whereby the ball may be reknapped by the rotary brush. Otherwise the ball dropping through the opening 94 will be immediately dispensed. The disks 88 are provided with ten vertical chutes 86 each of which is adapted to contain six tennis balls in such a manner that the balls may be dispensed one at a time through the opening formed in the sloping floor 84 of the receptacle so that they may 75

pass upon the rotary support 97 and be guided thereon by the guideway 99. The tennis balls are held in position upon the support 97 by means of an arm 100 secured to the receptacle 83 by means of the bracket 101 held in place by rivets or other fastening elements 102.

It will be noted that the rotary support 97 is mounted on a shaft 103 suitably secured to the crosspiece 105 having the ends thereof secured to the vertical frame member 23. Said rotary support 97 is provided with three faces 106, one of which has one depression where the ball comes to rest and the striking arm projects it in one and the same direction, the second face has two depressions 120 and 121 so positioned that the ball will come to rest in either one of the depressions by chance and the striking arm will project the ball in two directions to either corner of the tennis court. The third face 106 is smooth and level the ball coming to rest anywhere by chance and when struck by angled face of gut 117 will project the ball at different directions.

The reversible striking element mounted on the end of the arm 42 comprises as shown in Figures 5, 6 and 7, a shaft 107 secured to the free end of the striking element 42 by means of a nut 108 and provided on one end of the shaft 107 is a block 109 having a hub 110 for attachment to the end of the shaft 107 as by means of a screw 111 passing through the block 109 and having its threaded end screwed in the end of shaft 107, block 109 is moved away from block 112 thereby increasing tension of tennis strings 111. At the opposite end of the shaft 107 there is also provided a similar block having a hub 113 loosely mounted upon shaft 107 so that a coil spring 114 may normally urge the hub 113 away from the opposite block 109 this to take up the stretch in the strings and the give in a tennis racket frame at the time of impact with the ball. Rigidly secured upon the shaft 107 at the intermediate portion thereof is a guide block 115 drilled as at 116 for receiving a series of gut strings 117 which are trained around the guide blocks 109 and 112. The gut strings 117 extend through slots 118 formed in blocks 109 and 112 in the end walls as clearly shown in Figures 5, 6 and 7.

It will be noted that the striking element is adapted to pass directly above the tennis ball support 97 and "Top Spin" can be imparted to the tennis ball when striking face is tilted to strike the tennis ball above center and "Under-cut Spin" can be imparted to the tennis ball when striking face is tilted to strike the tennis ball below center.

Extending through the hollow shaft 89 is a driven shaft 125 on the upper end of which is rigidly secured a disk 126 provided with a circular brush 127. The periphery of the brush is adapted to contact the tennis ball falling within the chamber 95 for the purpose of cleaning and re-knapping the balls after they have been used and worn smooth in regular play.

The lower end of shaft 125 is provided with a pulley 125a around which is trained as shown in Figure 4 a belt 129 extending over sheaves 130 mounted on axle 131 carried by a bracket 132 rigidly secured to one of frame plates 24 by a nut and bolt 133. The endless belt 129 passes downwardly and is trained over the armature pulley 29 mounted on the armature of the motor 26. Disk 128 attached to shaft 89 is provided with five slots 134 carrying rollers 135 which are

adapted to engage a cam portion 136 formed intermediate the ends of a pivoted lever 137, one end of which is pivoted to a bracket 138 secured to one side frame plate member 24 by screws 139 and a pivot pin 140 extending through the bracket 138 and through one end of the lever 137 and is held in place by a cotter pin 141. The free end of the pivoted lever 137 extends through a slot in the opposite frame plate member 24 and is provided with a link 142 having one of its ends received in an opening 143 and its opposite end pivotally secured in the upper portion of the frame member 21 as at 144, and capable of being adjusted by means of the thumb screw connection 144a as shown in Figures 2, 3 and 8.

As shown in Figure 8, the link 142 is detached from the connection 143 and from the upper end of the support 21 whereby the frame 24 may be held stationary by passing the thumb screw through the supporting frame a sufficient distance 20 to engage the series of apertures 142a formed in a plate 142b secured to the frame plates 24. When the thumb screw is engaged with the plate 142b as above described, the link 142 will be in the position shown in Figure 8 and when it is 25 desired to tilt the frame at every other shot the link 142 is connected to the end of the cam bar 137 as at 143 by means of the thumb screw 144a thereby making it necessary to withdraw the thumb screw as shown in Figure 8 and with the 30 same connect lever 137 at 143 to link 142 which is attached to frame 19. Three different tilting angles are possible by connecting thumb screw in three separate holes in link 142.

As disk 128 rotates, the lever 137 is rocked on 35 its pivot 140 which causes the swinging frame 23 to be rocked on its pivot 22 with respect to the stationary frame 19 whereby tennis balls may be projected alternately in high or low trajectories.

Automatic means is provided for stopping the 40 motor 26 after a predetermined number of balls have been projected and said means comprises a cam 150 mounted upon one end of the shaft 36 adapted to engage a pivoted dog 151 which may be secured to the frame piece 24 and may have 45 its end held into engagement with a ratchet wheel 152 secured to a stub shaft 153 mounted on a suitable bracket 154. The opposite end of the stub shaft 153 is provided with a hand knob 155 having a pointer 156 adapted to register with 50 the graduations on a dial attached to side frame piece 24. One end of a spring 157 is presented to the ratchet wheel 152 in a frictional manner to hold the wheel in position after it has been 55 stepped a single notch by the pivoted dog 151. The spring 157 is connected to one of the frame plates 24 as at 159 and has its opposite end encircling the ratchet wheel 152 and is connected to the pivoted dog 151 for normally holding the pivoted dog into engagement with the teeth on the ratchet wheel 152. A stud is adapted to be secured to one of the radial faces of the ratchet wheel 152 and said stud may engage the arm of a snap switch which may be in a suitable circuit. 60 The switch is not shown but any form of conventional snap switch may be provided having a pivoted lever sufficiently long enough to be engaged by the stud carried upon the ratchet wheel 152. By adjusting the pointer 156 to the graduations on the frame plate 24 (not shown) said 65 graduations may be in the terms of a number of balls projected, which setting will bring the stud on the ratchet wheel 152 into position so that after a predetermined number of balls have been 70 75

shot and the shaft 36 has been rotated a predetermined number of times to cause the cam 150 to step the ratchet up to the desired number of balls projected the stud provided on the ratchet 5 wheel will engage the switch arm and break the circuit through the power supply and motor 26. The motor 26 effects rotation of the shaft 31 by means of the belt and pulley connection between the pulley 28 of the motor and the pulley 33 on 10 the shaft 31, rotation of the shaft 31 being transmitted by the worm and worm wheel devices to the disk 47 that carries the dog 48 for rotation of the drum 51 that effects rotation of the stub shaft 40 carrying the striker arm 42. The striker arm 15 42 is moved in a counter-clockwise direction from the position shown in Figure 3 by action of the motor drive and during such movement, the tension devices 57 and 58 have the tension thereon increased by movement of the strap members 55 20 and 56 so that when the dog 48 is released from its engagement with the drum 51, the spring devices 57 and 58 effect a sudden clockwise movement of the striker arm 52 for impinging the ball 25 for the delivery thereof.

25 It is to be understood that the form of the invention herewith shown and described is to be taken as the preferred embodiment of the same and that various changes in the shape, size and arrangement of parts may be resorted to 30 without departing from the spirit and scope of the invention as claimed.

I claim:—

1. A ball projecting machine comprising a base member, a swinging frame carried by the base 35 frame, a receptacle secured to the upper end of the swinging frame adapted to receive a plurality of balls in stacked relation, means for dispensing said balls singly, a support for receiving said balls having a plurality of curved surfaces and 40 different depressions, and means for projecting

said balls after they have been dispensed upon said support.

2. A ball projecting machine comprising a base frame, a swinging frame carried by the base frame, a receptacle secured to the upper end of the swinging frame, means in said receptacle for supporting a plurality of balls in stacked relation, means for dispensing said balls singly, a support for receiving said balls having arcuately curved surfaces, a striking arm for engaging 10 said balls for projecting the same in one or different directions, means for operating the striking arm and means for swinging said frame with respect to the base frame whereby different trajectories may be imparted to said balls. 15

3. A ball projecting machine comprising a base frame, a swinging frame carried by the base frame, means for dispensing a plurality of balls carried by the upper end of the swinging frame, a support for receiving said balls, a striking arm 20 for engaging the balls and projecting the same in one or different directions, means for operating the swinging arm comprising a driven shaft, a motor for driving said shaft, a clutch connecting said shaft to the swinging arm, and means for 25 tripping said clutch.

4. A ball striking machine having a striking arm, means for operating the striking arm comprising a motor driven shaft, a clutch for connecting the motor driven shaft to the striking 30 arm, means for placing the striking arm under tension and means for tripping said clutch.

5. A ball striking machine having a striking arm having a ball engaging member on the free end thereof which is strung with regular gut 35 strings one surface a flat plane for projecting the balls in one direction and the opposite surface with two planes at angles to each other for projecting the ball in different directions.

EDMUNDO H. SERRANO. 46
